HOSIERY PROTECTOR

Filed Sept. 19, 1928

Inventor:
Joseph DRAIKIN
By: MANNED. BAYNE
Atty

UNITED STATES PATENT OFFICE

JOSEPH DRAIKIN, OF CHICAGO, ILLINOIS

HOSIERY PROTECTOR

Application filed September 19, 1928. Serial No. 308,829.

The present invention relates to protectors for hosiery in general and more especially to an improved and novel light and very transparent hosiery protector, more particularly 5 those worn by women and girls.

It is well known that in bad weather the heels of the shoes will kick up the water or slush on the back part of the hosiery, around the ankle and calf of the leg, causing the hosiery to become wet and dirty, resulting in a great deal of inconvenience to the wearer. Also the dripping of water from coats and especially from slickers is a source of a good deal of trouble to women in bad weather, as 15 well as the splashing of water and slush upon a person's hose by passing vehicles when attempting to pass too close to vehicles in going over a crossing.

With these facts in view it is the main object of the present invention to provide a hosiery protector of the character described which will not only prevent the soiling of the hose, but will also be neat in appearance and made of such a material which will permit 25 the same to be folded in a small and compact package which may be easily carried in a lady's handbag or the like.

Another object of the invention is to provide a protector of the character described 30 which may be constructed of a transparent rubberized fabric, such as silk, or the like, and which is shaped to conform to and fit about the ankle and calf of the leg, said protector being provided with novel and im- 35 proved means for preventing the same from slipping down when applied to the leg of a person.

A further object of the invention is to provide a protector of the character named, 40 which may be easily and cheaply manufactured, compact and neat in appearance, easily carried around from place to place, and which will be efficient in carrying out the purposes for which it is designed.

A still further object of the invention is 45 to provide a hosiery protector of the character described, which is provided with novel and improved fastening means on the inside thereof for preventing the same from slipping when fastened on the leg, said fasten-

ing means comprising a suitable strap, or the like, adapted to surround the calf of the leg, and to be fastened thereabout.

A still further object of the invention is to provide a novel and improved protector of 55 the character described, which will be water proof, very transparent, light, and which will fit snugly and neatly on the leg to protect the stockings from becoming splashed or soiled in bad weather, and which may be folded 60 when not in use into a small and compact package which will readily fit in a lady's handbag, or the like.

With the foregoing and other objects in view, which will appear as the description 65 proceeds, the invention consists in certain novel and improved features of construction, arrangements, and combination of parts, hereinafter more fully described, illustrated 70 in the accompanying drawings, and particularly pointed out in the appended claim, it being understood, that various changes in the form, size, and minor details of the structure may be made without departing from the 75 spirit or sacrificing any of the advantages of the invention.

Stated generally, the invention comprises a hosiery protector made in the form of a gaiter or legging, and which is designed to be constructed of a very thin and very transparent 80 rubberized fabric, such as silk, or the like. The said protector is designed to fit snugly around the ankle and calf portion of the leg, as well as around the heel and instep portions thereof for proving a maximum amount 85 of protection from splashing water or slush, and the like.

The said protector is also provided with suitable fastening means along the outer edges thereof for securing the same in place 90 when applied to the leg of a person, as well as having a suitable strap provided on the inside thereof adapted to go around the calf portion of the leg for preventing the said protector from slipping since the material 95 thereof is very light in weight. A suitable arch strap of usual and well known construction is also provided on said protector, for further aiding in the application thereof to the leg.

For facilitating an understanding of my invention, I have illustrated in the accompanying drawings, preferred embodiments thereof, from an inspection of which, when considered in connection with the following description, my invention, its mode of construction, and many of its advantages should be easily understood and appreciated.

Referring to the drawings, in which similar characters of reference are employed to indicate corresponding or similar parts throughout the several figures in the drawings:—

Fig. 1 is a view in perspective illustrating one embodiment of the improved protector showing the same applied to the leg of a person;

Fig. 2 is a plan view illustrating the protector in open position;

Fig. 3 is a view in side elevation of a modified form of the invention, the same being constructed of two blanks instead of three as used in the first modification; and

Fig. 4 is a view in side elevation of still another form of the invention, wherein the upper form of the protector may be turned down to produce what is commonly known as the "pirate boot" effect.

Referring more specifically to the drawings, the reference character 10, designates the main body of the protector or legging, the same being made of very thin and transparent water-proof fabric, such for example, as silk or the like, and shaped to conform to the general contours of the calf and ankle portions of the wearer, so as to comprise an instep covering portion 11, at the front thereof, a heel covering portion 12, at the back thereof an ankle embracing portion 13, adjacent the instep and heel covering portions, and a calf embracing portion 14, at the upper end thereof.

In the embodiment illustrated in Figs. 1, and 2, of the drawings, the legging or protector 10, is composed of three blanks, a main or central blank 15 and two lateral, or side-blanks 16 and 17. The main blank is suitably curved along its sides to adapt it to snugly and neatly fit around the calf portion of the wearer, and is widened at the bottom to form the toe or instep portion 11, at the front thereof, and the heel portion 12, at the back thereof. The lateral blanks 16, and 17, have respectively approximately straight outer edges 18, and 19, but at their inner edges have respectively curvatures 20, and 21, substantially precisely the same as those of the edges of the main blank 15. The respective blanks are attached together in any suitable and well known manner, such as by stitching, or the like. All of the marginal edges of said legging or protector 10, may be turned in and stitched, as indicated at 22, and 23, in Fig. 2, to produce neat, even, and smooth marginal edges therefor. The re-

sultant legging or protector will thus be extremely neat in appearance and will be shaped to provide at the lower portion thereof of sufficient extra material for snugly engaging the instep and heel portions of the foot, and will be suitably shaped at the upper portion to snugly embrace the calf portion of the leg, as is apparent from an inspection of Fig. 1, of the drawings.

A suitable arch strap 24, made out of the same material as the body portion of the protector, is attached as at 25, in any suitable manner, such as by stitching, or the like, near the lower edge of the main blank 15, preferably substantially at the middle thereof. The strap 24, has at its extremity provided a suitable fastening means, such as the female member 26, of a snap fastener for connecting the said strap to the lower edge of the lateral blank 16 which is provided with the male or stud member 27, of said fastener. For securing the said protector around the leg of the wearer, I provide suitable snap fasteners along the outer edges of the lateral blanks 16, and 17. These fasteners include a male member or stud 28, near the lower edge of the lateral blank 16, and a succession of studs 28, preferably at equal intervals along said edge. The opposite lateral blank 17, is provided with mating or the female members 29, of said snap fasteners, which are disposed at the same levels as those of the studs 28.

The protector conforms neatly to the shape of the leg well up over the calf, and in order to prevent the same from slipping down, since the material is very thin, I provide an inner strap 30 which is also made of the same thin, transparent material. This strap is made of sufficient length to fit tightly around the calf, and is connected in any suitable manner intermediate the ends thereof to the body of the protector on the inner side thereof, as shown at 31 in Fig. 2. The strap 30, has its extremities provided with suitable fastening means such as the snap fastener 32, for connecting the ends of said strap together, when the same is applied to the leg of the wearer.

In the modified form illustrated in Fig. 3, the protector or legging 40, is similar in every respect to the embodiment illustrated in Figs. 1, and 2, only that said protector 40, is constructed of two blanks, 41, and 42, instead of the three blanks employed in the first form. The resultant protector is fastened at the back as shown in Fig. 3. Otherwise, the construction of this modification is the same, and for that reason it is deemed unnecessary to further describe the construction of the same.

In the modification illustrated in Fig. 4, of the drawings, the top portion of the protector is flared a sufficient amount to permit it to be turned down as at 51, to produce what is known as the pirate boot effect. The

protector 50, of this modification is otherwise constructed similar to the form illustrated in Figs. 1, and 2, of the drawings.

When the protector is applied to the leg of the wearer and secured in place thereon, it will extend over the instep and heel of the foot, as well as up around the ankle and calf, the same will so cover and enclose the parts as to efficiently protect the stocking from becoming wet or damp, and also from spattering by muddy water, mud or the like, thus affording a very desirable protection from both standpoints of health as well as appearance. It will be understood that the novel protector may be made in desirable color effects, so that in and of itself it will provide an attractive feature of dress, especially for women.

The legging or protector is to be made of very light and very transparent material which will thus give the same appearance to the apparel when the same is worn by a person, as when the wearer may discard the protector, in good weather. Also because of its lightness, the said protector may be folded into a small and compact package which may be easily carried around in a woman's handbag, or the like, thus making it available for use whenever found necessary or desirable.

It is believed that my invention, its mode of construction, and many of its advantages should be readily understood from the foregoing without further description, and should also be manifest that while preferred embodiments of the invention have been shown and described for illustrative purposes, the structural details are nevertheless capable of wide variation within the purview of my invention, as defined in the appended claim.

What I claim and desire to secure by Letters Patent of the United States is:

A protector for hosiery constructed of a very thin and transparent water-proof material, which is adapted to snugly fit around the leg of a person for protecting the hosiery, the uppermost portion of said protector flaring upwardly and outwardly, whereby the said upper portion may be turned down to give the appearance of a pirate boot, and a strap provided on the inner side of the protector adjacent the upper edge thereof adapted to surround the calf portion of the leg and to be securely fastened thereabouts for maintaining the said protector in an upstanding position, said protector being adapted to be folded into a small and compact package which may readily fit into a lady's handbag.

In testimony whereof I affix my signature.
JOSEPH DRAIKIN.
